UNITED STATES PATENT OFFICE

2,442,753

ELECTROLYTIC AMALGAMATOR WITH
ADJUSTABLE ELECTRODES

Martin J. Barker, San Francisco, Calif.

Application November 27, 1945, Serial No. 631,145

3 Claims. (Cl. 209—179)

1

The hereinafter described invention relates to an apparatus for the recovery of fine and/or oxidized gold from ores, and the object of the invention is essentially to recover those values which at present may be lost by being carried away with the tailings.

The invention resides in a novel electrical sluice box utilizing mercury as an amalgamating agent, means being provided for applying an electrical current between electrodes submerged in the water filled sluice box and the mercury, for the purpose of cleaning and brightening the mercury and also for cleaning and brightening the gold, and for the further purpose of making the mercury receptive to the gold particles, thus assuring a more positive amalgamation, especially with respect to the finer particles of gold which are difficult to extract by methods known by me to be presently in use.

It is an object of the invention to provide a simple, easily constructed rugged device for accomplishing the purposes set forth above, and especially to provide a device of the character set forth in which the flow of electricity between electrode and mercury pool may be readily controlled, to assure most efficient operation of the device.

With the foregoing objects in view, together with such other objects and advantages as may subsequently appear, the invention is carried into effect as illustrated by way of example in the accompanying drawings, in which:

Figure 1 is an elevational view of an embodiment of the invention, partly in section; and

Figure 2 is a plan view of Figure 1.

Referring now specifically to the drawings, wherein like numerals of reference apply to the same parts in both views, 1a and 1b represent the wooden side walls of a sluice, which are spaced apart and held rigidly by a plurality of spacer rods 2 locked to each side wall by means of lock nuts 3, and located adjacent the upper edges of the walls 1a, 1b. An additional plurality of bolts 4 extending from wall to wall adjacent the lower edges of the walls 1a, 1b and under the copper bottom plate 5, retain the walls securely against the edges of the copper bottom 5, which is formed in a succession of gently falling slopes 6 and sharp rises 7.

The combination of the gently falling slopes 6 and the sharp rises 7 form a succession of receptacles or pools 8 in which is contained the mercury, which is utilized in the invention for amalgamating with gold particles, thereby to extract the gold. The sharp rises also form re-

2

tarding means for heavy particles, such as of gold.

Secured on rods 2 adjacent to the wall 1b are located a series of bell crank levers each having an arm 9 extending upwardly and an arm 10 extending at an angle of approximately 45 degrees to the horizontal downwardly toward the bottom of the sluice, one bell crank being located over each mercury pool 8. While two pools 8 and 10 two bell crank levers 9, 10 are illustrated in the drawings, it is to be understood that the number of such pools utilized in the practice of the invention is not of the essence of the invention but may be more or less than two, the number two having been selected for purposes of illustration only.

Mounted on each rod 2, at positions adjacent to wall 1a are located arms 11, which extend in parallel direction to arms 10 and are of similar length. Carried between rocker arms 10 of the bell crank levers 9, 10 and the arms 11 adjacent the lowermost points thereof are cylindrical electrodes 12, preferably of carbon, suitably secured to the arms 10 and 11.

25 An extension 13 of one crank arm 9 forms a convenient handle for actuating the series of bell cranks, which are interconnected by an actuating member or draw bar 14, secured to the crank arms 9 by means of pin rivets 15.

30 Since the electrodes 12 are immersed in the fluid which is passing down the sluice, they are subjected to forces which will prevent maintenance of the adjusted position of the electrodes, unless a suitable lock is provided. To provide for such contingency there is provided at a convenient location between a pair of bell cranks 9, 10, a lock means comprising a bracket 16 suitably secured to a side 1 of the sluice box, and extending upwardly beyond the highest possible point to 35 which actuating or draw bar 14 may rise in the adjustment of the device.

40 A cover clamp 17 is secured to the bracket by means of a pivot bolt 18 extending through both clamp 17 and bracket 16, and located adjacent to the top of wall 1. The clamp 17 extends to a point adjacent the top of the bracket where it is releasably secured to the bracket by means of a wing nut and clamp screw 19. The wing nut may be loosened when it is desired to adjust the 45 position of the electrodes 12, to permit actuation of the draw bar 14, and may be readily locked after the adjustment has been made.

A source of direct current voltage 20 is applied between each carbon electrode 12 and the pools 55 of mercury 8, by making a wire connection 21

between one of the bell cranks 9 and a pole of the source 20. This completes a circuit to all of the electrodes 12 since the carbon electrodes 12 are all connected electrically to the metallic system consisting of the actuating or draw bar 14 and the various bell cranks 9, 10.

The negative terminal of source of voltage 20 is connected by means of line 22 to the copper bottom 5 whereby voltage is conveyed to all the mercury pools 8, copper being an excellent conductor, as is well known.

The application of electricity between electrodes 12 and mercury pools 8 results in a cleaning and brightening of the surfaces of the mercury in the pools, and also acts to clean and brighten particles of gold passing through the sluice box and over the mercury, assuring a more positive action of amalgamation especially toward the finer particles of gold.

While I have shown and described a specific embodiment of my invention I do not limit myself to the exact details of construction set forth, and the invention embraces such changes, modifications and equivalents of the parts and their formation as come within the purview of the appended claims.

What I claim is:

1. In an amalgamator comprising a sluiceway having wooden sides, a metallic bottom member secured between said wooden sides, a series of tie rods for spacing said wooden sides, a plurality of compartments formed in said metallic bottom member, a quantity of mercury in each compartment, a plurality of cylindrical carbon electrodes one being located above each compartment, a plurality of rocker arms secured to said tie rods, means mounting said electrodes on said rocker arms, means for simultaneously actuating said plurality of rocker arms to adjust said electrodes with respect to said compartments, and means for applying voltage between each of said plural-

4
ity of electrodes and said metallic bottom member.

2. In an amalgamator having a sluiceway comprised of a metallic bottom member divided into receptacles each having a gently falling slope and a sharp rise, and an amalgamating agent in each receptacle, the combination of electrodes superimposed above said receptacles, pivoted arms mounting said electrodes at a uniform distance above the amalgamating agent in said receptacle, linkage interconnecting said pivotal arms, and an operating handle connected to one of said pivoted arms.

3. In an amalgamator having a sluiceway comprised of a metallic bottom member divided into a plurality of receptacles each having a gently falling slope and a sharp rise, and an amalgamating agent in each receptacle, the combination of electrodes superimposed above said receptacles, pivoted arms mounting each electrode at a uniform distance above the amalgamating agent in said receptacle, a link interconnecting said pivotal arms, a locking device cooperating with said link for holding the electrodes at a predetermined distance above the amalgamating agent in the respective receptacles, and an operating handle connected to one of said pivoted arms.
